UNITED STATES PATENT OFFICE.

ERNEST T. PEARSONS, OF CLEVELAND, OHIO, ASSIGNOR TO THE BAKER-RAULANG COMPANY, OF CLEVELAND, OHIO, A CORPORATION OF OHIO.

DOOR-OPERATING MECHANISM.

Application filed April 5, 1926. Serial No. 99,980.

This invention relates to a door opening and closing mechanism, particularly where the handle or operating device is located at a remote distance from the door, such as in 5 vehicles.

The invention finds its most useful application in connection with passenger vehicles of the commonly known "bus" type, wherein the operative occupies a position at one 10 side of the vehicle and a door is provided at the opposite side thereof to facilitate the movement of the passengers past the operative either in entering or leaving the vehicle and for other reasons.

15 One object of the invention is to provide improved and relatively simple operating and controlling mechanisms for a door permitting the latter to be disposed at any point in the vehicle body remote from the operative's position while insuring easy and positive operation of swinging the door in either direction and latching and unlatching it by the operative.

Another object of the invention is to provide 20 an improved door latching and unlatching mechanism in which provision is made for preventing the latching of the door except by operation of the handle or other operating device, thereby preventing the 25 complete closing and latching of the door from outside of the vehicle.

Another object of the invention is to construct a vehicle in which the door and the operating devices are separated from each 30 other and to connect the door and operating devices by an improved mechanism of relatively simple construction and capable of being incorporated in the walls of the vehicle in a ready manner, whereby braces, 35 operating links or levers within the vehicle are avoided and increased space results.

A further object of the invention is to provide an improved door operating and latching mechanism in which is provided a 40 normally retracted latch and an operating element interposed in the operating connections whereby the latch is first operated in the opening movement of the door to effect release thereof from its keeper and is operated at the end of the closing movement of 45 the door to effect the latching of the latch behind its keeper.

Other objects of the invention will be apparent to those skilled in the art to which 50 my invention relates from the following de-

scription taken in connection with the accompanying drawings, wherein.

Fig. 1 is a fragmentary view of a vehicle, partly in plan and partly in section.

Fig. 2 is a fragmentary section of the vehicle wall, enlarged, and showing the controlling devices and a portion of the operating mechanism with portions thereof in section.

Fig. 3 is a section on the line 3—3 of 65 Fig. 2.

Fig. 4 is a section on the line 4—4 of Fig. 2.

Fig. 5 is a section on the line 5—5 of Fig. 2.

Fig. 6 is a section on the line 6—6 of Fig. 2.

Fig. 7 is a fragmentary sectional view showing the door in closed position, door latch in latching position, a portion of the 75 operating mechanism and the latch controlling means.

Figs. 8 and 9 are sections on the lines 8—8 and 9—9, respectively, of Fig. 7.

Fig. 10 is a fragmentary view of the vehicle side wall adjacent the door, looking 80 toward the right of Fig. 7.

Fig. 11 is a fragmentary sectional view of the parts shown in Fig. 7, but showing the position of the latch and the controlling 85 means therefor, either at the time the latch is operated to release the door to open it or at the time the door is closed but before these means are operated to position the latch behind its keeper.

Fig. 12 is a fragmentary section similar to Fig. 7, but showing the door open.

Fig. 13 is a section on the line 13—13 of Fig. 12.

Fig. 14 is a section on the line 14—14 of 95 Fig. 12.

In the drawings, 1 indicates a vehicle, preferably of the "bus" type. The vehicle may be of any standard or special form of construction, or similar to that disclosed in 100 the co-pending application filed by Edward J. Stahl on December 5, 1925, Ser. No. 73,433, see Letters Patent No. 1,622,240. The vehicle comprises a body 1 mounted on suitable wheels (not shown) and the necessary equipment and mechanisms for propelling and steering it in a well known manner. The body 1 is preferably of the closed type, having a floor 1^a, side walls 1^b, a frame 1^c forming a continuation of the side walls 105 1^b and a roof 1^d.

around the front portion of the body 1, the usual cowl 2 and hood 3; and the side walls 1^b are constructed to provide openings for suitable windows 4, 5, and a door 6, to which reference will later be made. The side walls 1^b and frame 1^c include horizontally disposed bars 1^b and 1^c respectively, to which certain elements (to be hereinafter referred to) are secured. The flooring 1^a 10 supports a plurality of seats A for passengers and a seat B for the operative, this latter seat being preferably arranged at the forward end of the flooring and adjacent the left side wall of the body 1, as is customary in vehicles of this type, and the door 6 being disposed in the right side wall thereof and toward the rear. However, it will be understood that the door 6 may be arranged at any desired point remote from 15 the operative's seat. The door 6 is preferably hinged along that side edge thereof nearest the operative, to simplify the operating mechanism and its connection therewith, suitable hinges 6^a being provided between 20 such edge and the adjacent portion of the side wall 1^b and a suitable keeper 7 being provided in the side wall 1^b adjacent the free side edge of the door 6, whereby the latch 8, which is preferably mounted to 25 slide endwise on the door, will latch the door closed or release it, whereby the door may be opened.

9 indicates a casting fashioned to provide a base 10 having wings 10^a which are suitably secured to the bar 1^c (preferably to the right of the operative's seat B and the steering wheel C), a bracket 11 and a casing member 12 in spaced relation to the bracket 11. The casing member 12 is provided with 30 a flange 13 to which the flange 14 of a casing member 15 is removably secured by screws 16. The walls of the casing members 12 and 15 and the bracket 11 are formed with aligned openings 12^a, 15^a and 11^a, respectively, and the walls of the openings 11^a and 15^a are screw threaded to receive screw threaded plugs 11^b, 15^b, respectively. The plugs 11^b, 15^b, serve as bearing elements for a shaft 16. By preference, I form in the 35 inner ends of the plugs 11^b, 15^b, and opposite ends of the shaft 16 substantially semi-spherical recesses or sockets 17 and interpose between each shaft end and the inner end of the adjacent plug a relatively large ball 18, whereby friction in the bearings is reduced; the recesses being so disposed that the centers of the balls will be in alignment with the axis of the shaft 16. Each plug 11^b, 15^b, is provided with a kerf 19, whereby it 40 may be engaged by a suitable tool and rotated, the effect of which operation will be to move the plug endwise and adjust the adjacent bearing. By providing screw plugs 11^b, 15^b, as mountings for both ends of the shaft 16, they may be operated to raise or lower the

shaft to any desired position. As shown in the drawings (Fig. 3), the casing member 15 is provided with a hollow boss 20 the opening in which receives the plug 15^b.

As shown in Fig. 3, the casing members 12, 15, are (1) shaped to form a chamber 10' to receive and enclose a power element, preferably a sprocket 20', which is suitably keyed to the shaft 16 and is preferably supported thereby in spaced relation to the inner walls of the casing members; and (2) secured together in a liquid tight manner so that a suitable lubricant may be placed in the chamber 10', if desired. The purpose of the sprocket will later appear. 75

80

21 indicates a crank having a hub 21^a fitting between the casing member 12 and bracket 11, and suitably keyed to the shaft 16. The outer portion of the crank is hollowed out to enclose a plunger 22; and the inner portion adjacent the hub 21^a may be offset (as shown at 21^b) to position the plunger in the plane of the bracket 11, whereby the plunger 22 may engage recesses (to be later referred to) formed therein to control the movement and positioning of the crank 21; the off-set 21^b is formed with an opening 21^c which serves as a guide for the outer portion of the plunger 22. Rearwardly of the off-set 21^b, the plunger 22 has an enlarged 90 portion 22^a the purpose of which is (1) to form a shoulder to abut the inner wall of the off-set 21^b and thus limit the inward movement of the plunger and (2) provide an abutment for the inner end of a compression spring 23 which normally tends to move the plunger inwardly; the outer end of the spring engages a pair of spaced lugs 23^a disposed at either side of the plunger 22. The outer end of the plunger 22 carries a lug 24 to which is pivoted a crank arm 25 on the lower end of a shaft 26, rotatably mounted in a suitable bearing 27. The bearing 27 is formed in up-standing integral walls 28 at the outer end of the crank 21. The upper end of the shaft 26 forms a handle 26^a for the operative to grasp, whereby the shaft 26 may be rotated, such operation serving to retract the plunger 22 against the tension of the spring 23. The handle 26^a is provided with a collar 28^a engaging the upper end of the bearing 27 and co-operating with a nut 29 screw threaded on the lower portion of the shaft and engaging the lower portion of the bearing 27 to hold the shaft 100 therein against endwise movement. The crank arm 25 is also preferably threaded on the lower end of the shaft 26 and locked in position by a nut 30. To permit of the 105 swinging movement of the crank 25, the plunger 22 is formed in sections and these sections are pivoted together by a pin 22' (see Fig. 3). 115

31, 31^a, indicate recesses formed in the side wall of the bracket 11, the former recess be- 110

130

ing positioned to receive the inner free end of the plunger 22 when the crank 21 is moved to the position to completely open the door 6 through an operating mechanism, indicated as an entirety at 32, and the latter recess being positioned to receive the free end of the plunger 22 when the crank 21 is moved to the position to completely close the door and cause the latch 8 to engage or be projected behind the keeper 7. Intermediate the recesses 31, 31^a, the side wall of the bracket 11 is formed with a slot 33 to receive the free end of the plunger 22 and the end wall of the slot 33 adjacent the recess 31^a forms a stop 33^a which limits the movement of the crank 21 and hence prevents the door 6 from being completely closed, so that it cannot be closed from the outside of the body 1 or in any manner except by the retraction of the plunger 22 and further movement of the crank 21.

Of the operating mechanism 32, 34 indicates a thrust member preferably comprising a flexible section 35, adapted to conform and accommodate itself to the straight and curvilinear walls constituting the body walls 1^b, 1^c, a reciprocating bar 36 slidably supported in the wall 1^b adjacent the door 6 and connected at its inner end to the flexible section 35 and a link 37 pivotally connected at its inner end to the outer end of the bar 36 and means, indicated as an entirety at 38 for controlling the latch 8. The controlling means 38 are connected to the outer end of the link 37 and operated by the crank 21 and the thrust member 34 in the manner to be later set forth. The inner end of the flexible member 35 terminates in a sprocket chain, which is arranged to engage with and be operated by the sprocket 20. By preference, the entire length of the flexible section 35 is made up of a single section of sprocket chain, such construction simplifying the assembly and construction of the flexible member and its guide 39 and providing for anti-friction bearings on the flexible member for rolling engagement with the walls of the guide 39.

As will be understood, the sprocket chain 35 comprises side bars connected by pintles and rotatable sleeves 35^a surrounding the latter, which sleeves slide between or roll on spaced guide surfaces 39^a provided within the guide 39. As will be noted in the drawings, the guide surfaces 39^a are spaced apart sufficiently to receive between them the sleeves and to guide them through the channel, without permitting buckling of the chain links or vibration thereof to cause rattling. The guide 39 comprises a pair of related bars or strips 39', 39", which are shaped or bent to conform to the front and side walls of the body, being preferably secured to the bars 1^b, 1^c (see Figs. 5 and 6). The inner strip 39' may be secured to the bars and the outer strip then secured to it, as shown in Fig. 5. The inner opposing walls of the strips 39' are channeled to form the guide surfaces 39^a and grooves 39^b at either side thereof to provide ample space for the movement of the side bars of the chain links without rubbing engagement with the strips. The inner end of the guide 39 is connected to the casting 10 in any suitable manner and its guide channel aligns with a similarly shaped channel formed in a sleeve 40 extending tangentially of the pitch circle of the sprocket and merging into the chamber 10', whereby the chain is guided to and from the sprocket 20' without danger of it buckling. As will be understood from Figs. 2 and 3, the side walls of the chamber 10' are disposed relatively close and concentric to the free ends of the sprocket teeth, so that the chain is maintained in operative relation to the sprocket 20' when the latter is rotated in either direction by the crank 21. The sleeve 40 fits within an opening 41 formed in the thickened walls of the casing members 12, 15 (see Fig. 4). At its outer end, the chain 35 is pivotally connected to the slide bar 36, which is shaped in cross section (see Fig. 6) to slidably fit the channel between the strips 39'. A portion of the outer strip 39', extending inwardly from its outer end is cut away, as shown at 42, in the plane of the link 37, so that the latter is free to swing inwardly to the position shown in Figs. 7 and 11, which position it occupies when the door 6 is closed.

Of the latch controlling means 38, 43 indicates a rod threaded at its outer end into a screw threaded opening 44 formed in the inner end of the latch 8 and locked in their adjusted relation by a nut 45. The inner end of the rod 43 is screw threaded into the outer end of a tubular member 46, the inner end of which terminates in a lug or knuckle 47 (see Fig. 7). The knuckle 47 is pivoted to one end of a rocker 48, triunnioned at 48' between the upper and lower walls of a casing 49. The casing 49 is secured to the inner side of the door 6 and preferably extends to the free side edge thereof to enclose the tubular member 46, rod 43 and inner portion of the latch 8 or a suitable guide 8' therefor. The opposite end of the rocker 48 is pivotally connected to the outer end of the link 37. 50 indicates an angle plate fixed to the inner side wall of the casing 49; the lateral flange of the plate being bifurcated and straddling the rod 43 to form an abutment 50^a. 51 indicates a coiled spring surrounding the rod 43 and interposed between the abutment 50^a and a washer 52 seated against the outer end of the tubular member 46. The purpose of the spring 51 is to act on the tubular member 46 and through it and the rod 43 to normally hold the latch in retracted position,

as shown in Fig. 11. The spring 51 is preferably strong enough to move the latch 8 and the rod 43 connected thereto, and operating mechanism 32 and crank 21 to the position shown in Fig. 11, unless these parts are held by the operative, so that upon the rotation of the handle 26^a to release the plunger 22 from the recess 31^a, the spring 51 will move the rod 43 inwardly and it in turn will swing the rocker 48 to the position shown in Fig. 11. By imparting to the spring sufficient strength to operate these parts, it will insure immediate release of the latch 8 from the keeper 7 upon the disengagement of the plunger 22 from the bracket 11.

Operation: Figs. 1 and 7 show the position of the parts when the door 6 is closed and latched. In this position the plunger 22 is projected into the recess 31^a, which locks the shaft 16 and sprocket 20' against movement, and the latch 8 is locked behind the keeper 7. If now the handle 26^a is rotated clockwise, the plunger 22 will be moved out of the recess 31^a, whereupon the spring 51 will move the latch 8 inwardly to the position shown in Fig. 11; then movement of the handle 26^a and crank 21 to the position shown in dotted lines in Fig. 1 and full lines in Fig. 2, will swing the door 6 to its full open position, in which position the plunger 22 projects into the recess 31 and locks the door against movement. Release of the plunger 22 and movement of the crank 21 in the opposite direction will close the door 6. As hereinbefore set forth the door will become closed (see Fig. 11) when the plunger 22 engages the stop 33^a, but since the spring 51 is strong enough to prevent relative movement of the operating parts, and outward movement of the latch 8, the latter remains in its retracted position during the operation of the crank 21 to close the door. To latch the door 6, it is necessary to swing the crank 21 a further distance, to thereby rock the rocker 48, overcome the tension of the spring 51 and push the latch 8 behind the keeper 7. In moving the crank 21 to effect this movement last mentioned, the plunger 22 is brought into registry with the recess 31^a and then projected therein, the effect of which will be to lock the latch 8 in latching position.

It will be noted that the plunger 22 and recesses 31, 31^a, constitute a trigger mechanism to retain the door 6 locked or fully open. By providing additional recesses, the door can be locked in any intermediate position.

It will be noted that if the swinging of the door to closed position is resisted, by lack of lubrication in the hinges 6^a or by reason of the fact that the vehicle is standing on an inclined surface, the resistance so set up will overcome the tension of the

spring 51 and accordingly the pull on the thrust member 35 will operate to compress the spring and project the latch outwardly, and the latter will thereby engage the outer surface of the body and prevent the door from being closed. To prevent this condition and operation, I have provided an automatic lock and release means (indicated as an entirety at 52) for the latch 8, whereby it is normally locked in its retracted position following the opening of the door 6 and it remains locked until the door approaches its closed position, when the latch is released to permit the operating means and thrust member to project it into engagement with the keeper 7. Accordingly, by the provision of the lock and release means 52, the pull on the door to close it is transmitted therethrough to the door instead of the spring which retracts the latch. Of the lock and release means 52, 53 indicates a collar adjustably fixed to the tubular member 46. 54 indicates a frame mounted on the door 6 within a chamber 6^a formed therein. 55 indicates a flat spring secured at one end to the inner wall of the frame 54 and carrying near its free end a lug 56 adapted to engage the collar 53 to lock it against movement outwardly due to the operation of the crank 21 and thrust member 32 when they are operated to close the door 6. The collar 53 and lug 56 are so disposed that when the latch 8 is retracted under the influence of the spring 51, the collar 53 will ride the inclined side face of the lug 56 and come to rest behind its end wall, whereupon the lug 54 will return to its normal position in the path of movement of the collar and thus lock it and through it and the rod 43, lock the latch in retracted position. The free end of the spring 55 is bent laterally to form an inclined surface, the purpose of which will later appear. 57 indicates a plunger slidably mounted in aligned openings formed in lugs 58, which are provided on the frame 54. The plunger is made in sections 57^a, 57^b, threaded together whereby its length can be adjusted. The section 57^b is provided with a flange or annular shoulder, so that (1) a coiled spring 59 interposed between the inner lug 58 and said flange normally operates to press the plunger endwise and (2) the flange may engage the outer lug 58 to limit the movement of the plunger 57 under the influence of the spring 59. As shown, the plunger is normally arranged to project beyond the inner side edge of the door, which position it occupies when the door 6 is open (see Fig. 12), but when the door is closed, the plunger 57 is in effect pushed inward due to its engagement with the body side wall 1^b (see Fig. 7). At its inner end, the plunger 57 carries a wedge 60 disposed in the path of movement of the inclined wall on the free

end of the spring 55. Accordingly, as the door moves toward its closed position, the wedge 60 will engage the spring 55 and swing it laterally (see Fig. 7). This movement moves the locking lug 56 out of its locking position and releases the collar 53, so that the rod 43 and latch 8 are free to be actuated outwardly.

Fig. 7 shows the door closed, with the latch 8 in latching position. If the handle 26^a and crank 21 are operated to open the door, the plunger 57 will slide outwardly and the latch will slide inwardly. In this movement of the latch, the collar 53 will move to a position behind the lug 56 (see Fig. 11).

In the closing movement of the door, these parts will remain in this locked relation until the door 6 approaches its closed position, whereupon the plunger will be arrested by its engagement with the side wall 1^b, so that in the further or continued movement of the door the spring 55 will be engaged by the wedge 60 and moved to release the lug 56 from the collar 53; then following the complete closing of the door 6, the operation of thrust member will project the latch 8 outwardly, against the tension of the spring 51, into position behind the keeper 7, as already set forth.

From the foregoing description it will be seen that the latch is locked in its retracted position and such locking provides in effect a positive connection between the thrust and pull member 32 and door 6, whereby the latter may be closed irrespective of the resistance to such operation due to any cause whatsoever that may at any time exist; but that as the door approaches its closed position, the lock is released to permit the free actuation of the latch.

To those skilled in the art to which my invention relates, many changes in construction and widely differing embodiments and applications thereof will suggest themselves without departing from the spirit and scope of the invention. My disclosures and the description herein are purely illustrative and are not intended to be in any sense limiting.

What I claim is:

1. In a vehicle, the combination with a body having a door, a keeper on the body and a movable latch on the door, of means for normally maintaining said latch in a retracted position, and mechanism for operating said door to open or closed position, said mechanism including relatively movable elements arranged to project said latch behind said keeper following the closing of the door.

2. A vehicle as claimed in claim 1 in which said relatively movable elements operate to disengage the latch from the keeper before effecting opening of the door.

3. A vehicle as claimed in claim 1 in which a locking means is provided to lock the operating mechanism and through it lock said latch in engagement with said keeper.

4. The combination with a vehicle provided with a wall having an opening, a door for closing said opening, a keeper carried by said wall adjacent said opening and a latch slidably mounted on said door, of means acting on said latch to normally maintain it out of engagement with said keeper, a rocker pivoted on said door and having one end connected to the inner end of said latch, and an operating mechanism connected to the other end of said rocker and arranged to operate the latter and through said rocker to effect disengagement of said latch from said keeper and operating through these elements to move said door to open position.

5. In mechanism of the class described, the combination of a support having a bracket and a casing member disposed in spaced relation, a separate casing member connected to said first mentioned casing member to form a chamber, the walls of said casing members and said bracket being formed with aligned openings, bearing elements positioned in the openings formed in said bracket and said separate casing member, a shaft extending through the opening in the first mentioned casing member and engaging said elements, a driven element within said chamber and connected to said shaft, and a driving element between said bracket and said first mentioned casing member and connected to said shaft.

6. A mechanism as claimed in claim 5 in which said bearing elements are screw threaded into their respective supporting openings.

7. A mechanism as claimed in claim 5 in which a ball is positioned between the inner end of one of said bearing elements and the adjacent end of said shaft with its center in line with the axis of the latter and their ends are formed with recesses to partially receive said ball.

8. A mechanism as claimed in claim 5 in which the driving element consists of a crank having an off-set to position its outer portion in the plane of said bracket, and a trigger mechanism having interengaging elements carried by said crank and said bracket.

9. In a vehicle, the combination with a body having a door, of an operating device supported by the body at a point remote from said door, and an operating mechanism between said device and said door, said mechanism including a rotatable element connected to said device, a flexible thrust member operatively connected to the door at its outer end and adapted to wind on and off said rotatable element at its inner end, and a guide for said member having op-

posed walls with which the intermediate portions of said member engage.

10. A vehicle as claimed in claim 9 in which the rotatable element comprises a sprocket and the flexible member consists of a sprocket chain having pintles that slidably engage the opposed walls of said guide.

11. A vehicle as claimed in claim 9 in which the rotatable element comprises a sprocket and the flexible member consists of a chain and the guide for the latter is shaped to engage only the opposite sides of the pintles for the chain links.

12. In a vehicle, the combination with a body having a door, of an operating device supported at a point remote from said door, and an operating mechanism between said device and said door, said mechanism comprising a rotatable element operated by said device, a flexible member arranged to wind on and off said element at one end, a slideable bar connected to the other end of said flexible member, a guide coextensive with flexible member between said device and said bar whereby the power of the latter may be transmitted endwise through said flexible member, and a linkage between said bar and said door.

13. In a vehicle, the combination with a body having a door in one wall thereof, of an operating device supported adjacent another wall of said body, a winding element connected to said device, a continuous guide carried by the walls of said body and conforming to the shape thereof and leading from said element to a point adjacent said door, a flexible member arranged to wind on and off said element at one end and slidably fitting and extending 40 through said guide, whereby the power of said winding element may be transmitted endwise through said flexible member when it is reciprocated in said guide, and a connection between the opposite end of said flexible member and said door.

14. A vehicle as claimed in claim 9 in which the rotatable element comprises a sprocket and the flexible member consists of a chain having rotatable sleeves surrounding the pintles for the links thereof and the

guide comprises spaced guide surfaces arranged to engage the opposite sides of said sleeves and through them guide said chain endwise.

15. In a vehicle, the combination with a body having a door, of an operating device supported on said body at a point remote from said door, a flexible member operatively connected to said door and said device and arranged to be moved endwise by the latter as a thrust and pull element to open and close said door, and a guide having opposed walls engaging intermediate portions of said flexible member.

16. A vehicle as claimed in claim 1 in which means are provided for automatically locking said latch in retracted position when the door swings open and for releasing it from the locking elements when the door moves into closed position.

17. A vehicle as claimed in claim 1 in which means, dependent upon the position of the door, automatically locks the latch in retracted position and release the same for projection behind its keeper.

18. A vehicle as claimed in claim 1 in which said door is provided with a catch serving to engage said latch to lock it in retracted position and a spring pressed plunger normally disposed in operative relation to said catch and in position to engage the body when the door is closed, whereby the closing of the door will operate said plunger and effect a release of the catch from said latch.

19. In a vehicle, the combination with a body having a door and a keeper, of a normally retracted latch, slidably mounted on the door, means for locking said latch in retracted position, means for operating said door to open and closed positions, and means for releasing said locking means as the door approaches its closed position, said operating means being operatively connected to said latch whereby it may be moved into engagement with said keeper.

In testimony whereof, I have hereunto subscribed my name.

ERNEST T. PEARSONS.
